Fig. 5.

To all whom it may concern:

Be it known, that I, Samuel L. Gerson, a citizen of the United States, residing in Wilmington, New Castle County, State of Delaware, have invented a new, original, and ornamental Design for a Combined Salt and Pepper Dispenser, of which the following is a specification, reference being had to the accompanying drawing forming a part thereof, in which:

Fig. 1 is a view in perspective of a combined salt and pepper dispenser showing my new design;

Fig. 2 is an exploded view in perspective showing the top of the dispenser separated from the body portion thereof;

Fig. 3 is a side elevational view of the dispenser;

Fig. 4 is a top plan view of the dispenser; Fig. 5 is an end elevational view of the dispenser; and Fig. 6 is a cross-sectional view in profile taken along line 6—6 of Fig. 3.

I claim:

The ornamental design for a combined salt and pepper dispenser, substantially as shown.
